(No Model.)

J. LEWIS.

BALANCED VALVE.

No. 365,135.

Patented June 21, 1887.

UNITED STATES PATENT OFFICE.

JOSEPH LEWIS, OF SOUTH EVANSTON, ILLINOIS.

BALANCED VALVE.

SPECIFICATION forming part of Letters Patent No. 365,135, dated June 21, 1887.

Application filed August 9, 1886. Serial No. 210,386. (No model.)

To all whom it may concern:

Be it known that I, JOSEPH LEWIS, a subject of the Queen of Great Britain, residing in South Evanston, in the county of Cook and State 5 of Illinois, have invented a new and useful Improvement in Balanced Valves, of which the following is a specification.

In valves used in all kinds of engines where water or other non-elastic fluid is used absolute accuracy of construction is necessary to insure steady working at high speed without pounding. This requisite accuracy includes correspondence between the various ports, both in the matter of size and relative positioning, 15 so that they may open and close at precisely the right time, and not an instant too early or an instant too late. My present improvements relate to a new method of construction, whereby this accuracy is easily secured and 20 repairs are greatly facilitated, as will be explained. The improvements are also applicable to and useful in valves for air or gas engines, although absolute accuracy of construction is not so important where elastic fluids 25 are employed.

The valves to which my improvements relate may have either a continuous rotary or an oscillating movement, and the nature of the improvements will be fully understood from 30 the annexed drawings and the following description.

In the accompanying drawings, which form a part of this specification, and in which similar letters of reference indicate like parts, 35 Figure 1 is a central longitudinal section of a valve and its chamber embodying my invention. Figs. 2 and 3 are sections on the lines 2 2 and 3 3, respectively, of Fig. 1. Fig. 4 is an exterior view of the cast shell forming the 40 body of the valve. Fig. 5 is an exterior view of the finished valve. Fig. 6 is a detached view of one of the rings previous to its application to the valve.

In said drawings, A represents the shell or 45 body of the rotary or oscillatory valve, and B the valve-chamber. The latter has an orifice, F, where the operating fluid first enters, and an annular chamber, E, receiving the fluid from said orifice. It is also provided with 50 ports 1, 2, 3, and 4, two at each end, and each pair at opposite sides of the chamber, these

ports leading to cylinders (not shown) having pistons operated by the fluid. The valve is provided with two heads, A' A'', each having two flattened sides, m, the flattened sides on 55 one head standing at right angles to those of the other head. The unflattened sides are cast with transverse openings n, extending from side to side of the valve and intersecting the central longitudinal passage, K. Upon 60 either head of the valve is a ring, a, of brass or other metal, shrunk or forced or otherwise secured thereon. In each of these rings are four port-openings the exact size required, two of which, diametrically opposite each other, 65 are placed over the openings n, and the other two, also diametrically opposite to each other, are located over the flattened sides of the valve-head. By making the passages n somewhat larger than the ports in the rings a slight range 70 of adjustment is allowed in positioning the rings. By thus forming the ports in the rings I am enabled to make them exactly of a size, and to locate them accurately both at right angles as respects the two pairs of ports and 75 at opposite sides as respects the individual ports composing each pair. I am also enabled to place them on the valve-shell so the ports of one ring will be in true alignment with those of the other ring. All these features are essential to the perfect working of 80 the device. The rings act in conjunction with the flattened sides of the valve-heads to form longitudinal passages o, giving egress to the water from annular chamber E to the ring- 85 ports adjoining the flattened sides. The rings also act to correct all inaccuracies in the valve-shell and obviate much of the care and nicety which would otherwise be necessary in casting and preparing it. The passages o are formed 90 without extra labor, instead of being cut or cast in the shell. Of course the ports are formed in the rings previously to putting them on the valve. The valve is slightly conical in 95 form and the chamber B is correspondingly shaped. The latter is also fitted interiorly with rings b, having each two previously-prepared openings, which are placed over the chamber-ports 1, 2, 3, and 4, so as to form the mouths thereof and so as to regulate the capacity and position of such mouths, said ports 100 being cast larger than requisite, as plainly in-

dicated by the drawings. These rings *b* should of course be equally as accurate in construction as the valve-rings, and should be placed in the chamber with the mouths or ports in position with the same precision. The rings *a* and *b* are thus made to form the bearing-surfaces of the valve and chamber, respectively, and they are the only portions thereof subject to wear. They can be readily removed and replaced by new ones whenever requisite, and the valve and chamber be thus made to last a lifetime by a very moderate expenditure. As they may be completely fashioned previous to application and of uniform sizes, they may be made of superior metal without large cost. They cure all inaccuracies in the castings, as well as such as are caused by boring the chamber and turning the valve, and they regulate and equalize the capacity of all the water-passages. It will be noticed that a line passing through one side of the openings in rings *b* intersects the axis of the valve, and that said openings are set off from this line one-eighth of the inside circumference of the rings; and it will be obvious from this disposition of the ports and construction that when the ports on one side of the chamber are closed those upon the other are open, and that each semi-rotation of the valve closes the open and opens the closed ports; and as the ends of the valve act alternately to feed and discharge the water it follows that the fluid will be alternately admitted to and discharged from the ends of the motor-cylinders with mathematical precision.

35 The drawings illustrate the valve when the ports on one side are opening and those on the other are closing, and in this position the di-

rections of the water-flow will be as indicated by the arrows in Fig. 1; but of course there will be no flow either way upon one side as soon as the ports about closing become entirely closed. I sometimes make the valves perfectly cylindrical, but prefer the slightly-conical form. The central discharge, *K*, is made to extend entirely through the valve, and is open at both ends, thereby equalizing the pressure upon the ends of the valve.

I claim—

1. The rotary or oscillating valve consisting of the cast shell having the water-passages and flattened sides and the port-forming rings, in combination with the casing having the lining-rings with ports located as specified, substantially as set forth.

2. The rotary or oscillating valve consisting of the plug having water ports and passages, as set forth, in combination with the casing *B*, having ports 1, 2, 3, and 4, and stationary bushing-rings *b*, provided with openings corresponding to said casing-ports and forming the mouths thereof, said openings being positioned as shown, substantially as set forth.

3. The combination, in a rotary or oscillatory valve, of a cast-metal shell having the water-passages *n* and flattened sides *m*, with separate rings having port-openings and secured on the shell with said openings located appropriately with reference to said passages and sides, substantially as specified.

JOSEPH LEWIS.
